COSMETIC POWDER COMPACT

Filed Sept. 4, 1928

INVENTOR

James Leslie Younghusband

By Charles Franklin Atte

UNITED STATES PATENT OFFICE

JAMES LESLIE YOUNGHUSBAND, OF CHICAGO, ILLINOIS

COSMETIC-POWDER COMPACT

Application filed September 4, 1928. Serial No. 303,640.

My invention relates to a compact for containing cosmetic powder and relates to one wherein the applicator or powder puff serves to cork the opening to the powder compartment, the applicator engaging between spaced flanges frictionally retained in the compact.

An object of the invention is to provide a compact for loose powder wherein the applicator serves as a closure for the powder compartment.

Another object is to provide a compact for cosmetic powder in which the applicator is held in position to close the powder opening by engagement between two spaced flanges.

Another object of the invention is to provide a compact having a flanged opening which defines the powder compartment and the entrance thereto in conjunction with another flange spaced above the first flange, with the applicator retained in position to close the powder opening by spring engagement with the second flange.

A further object is to provide a compact having a ring frictionally retained in the powder compartment under which the applicator is passed and by which it is retained in position to close the opening to the powder compartment.

A further object is to provide a compact having a receptacle for powder, with a wall member frictionally retained within the powder compartment, which wall member has two vertically spaced flanges between which the applicator is retained for closing the powder opening.

The above, other and further objects of the invention will be apparent from the following description, accompanying drawings and appended claims.

According to the invention, a powder receptacle is provided with a flanged opening defining the powder compartment and providing an entrance thereto, which flanged opening is made from a single sheet of metal bent to provide a peripheral rim from which extend two spaced flanges normal to the rim.

One embodiment of the invention is shown in the accompanying drawings and the views thereof are as follows:

Figure 1 is a front view of a compact partially opened embodying my invention.

Figure 2 is a plan view of the open compact.

Figure 3 is an enlarged vertical central section through the powder receptacle.

The form of the invention shown in the accompanying drawings comprises a bottom member or receptacle 1, a top 2 which is shown as hinged at 3 to the receptacle 1. I do not wish to be understood as limiting myself to the hinged connection between the top and bottom members as it is of course understood that these may be entirely separate.

The powder receptacle 1 has a dished bottom 4 with a circular wall 5 notched at 6 to receive the marginal flange of the top 2.

The powder compartment 7 is defined by the bottom 4 of the receptacle and a flange 8 substantially perpendicular to the wall 5.

The flange member carrying the flange 8 is made from a strip of sheet metal bent to form the flange 8, a peripheral web 9 to which the flange 8 is normal, an upper flange or ring 10 extending in the same general direction as the flange 8 and a lower margin 11 which rests in the junction between the bottom 4 and the wall 5 of the receptacle for supporting the flange member in position. The flange 8 is formed by bending back the metal of which the ring is formed on itself and then bending outwardly the end portion to provide the flange 8 which as so formed is of greater horizontal dimension than flange 10 defining an opening through the flange 8 of less diameter than the opening defined by the flange 10.

The flange 8 defines a central opening 12 through which the powder is reached. The diameter of the inner opening of the ring 10 is greater than the diameter of the opening 12.

An applicator 13 having a diameter less than that of the opening 12 and greater than that in the ring 10, closes the opening to the powder compartment by being sprung past the opening in the ring 10 to rest against the flange 8. The applicator being of greater diameter than the opening in the ring 10 extends part way under said ring whereby it

is retained in position to close the powder opening.

A top 2 may have a mirror 14 secured therein by a ring 15. A projection 16 is formed on the top to aid in opening the same.

While I have described more or less precisely the details of construction of my invention, yet I do not wish to be understood as limiting myself thereto as I am aware that changes may be made in the arrangement and proportion of parts and that equivalents may be substituted, all without departing from the spirit and scope of my invention.

I claim as my invention:

15 1. A compact for loose powder comprising a powder receptacle having a flanged opening therein, the flange defining said opening comprising a ring having a peripheral web frictionally engaging the wall of said receptacle and being coextensive with the same, a flange intermediate the margins of said web and normal thereto defining the opening to the powder compartment, and a second flange about the margin of said web spaced above said first flange and with less width than said first flange.

20 2. A loose powder compact comprising a receptacle for loose powder, a removable ring frictionally retained in said receptacle and defining the powder opening for the same, said ring having a peripheral web in contact with the wall of the receptacle and having an intermediate and a marginal flange normal to the web integral with the same, said 25 marginal flange having an inner opening of greater diameter than the opening in the intermediate flange, and an applicator closing the opening in the intermediate flange and retained in closed position in said opening by engagement with said marginal flange.

30 3. A loose powder compact comprising a receptacle for loose powder, a removable ring frictionally retained in said receptacle, said ring comprising a peripheral web coextensive with the inner wall surface of said receptacle and having an upper marginal flange and an intermediate flange normal to said web, the upper flange defining an opening of greater size than the intermediate flange and an applicator for closing the opening in said intermediate flange and locked therein by engagement with said marginal flange.

35 4. A loose powder compact comprising a receptacle for loose powder, a removable ring frictionally retained in said receptacle, said ring having a peripheral wall and two spaced flanges normal to said wall all formed from a single piece of sheet metal with one of said flanges between the top and bottom edges of said wall, the two flanges defining openings of different diameters with the intermediate flange defining the smaller opening, said wall being so shaped with respect to said intermediate flange as to support said flange above the bottom of the receptacle, the opening in

5 said intermediate flange constituting the entrance to the powder compartment, and an applicator closing said opening and locked therein by engagement with said marginal flange.

70 5. A container comprising a receptacle, a member adjacent the inside wall thereof and secured thereto, an inwardly extending flange at the upper edge of said member defining an opening into the receptacle, a reversely bent portion on the lower edge of said member and a second flange below the first flange formed at the upper edge of said reversely bent portion.

75 6. A compact for loose powder comprising a powder receptacle having a flanged opening therein, a double flanged ring frictionally retained in said receptacle and forming the flange for the same, and an applicator closing the opening and retained in closed position in said opening by engagement between said double flanges.

80 In testimony whereof I have hereunto subscribed my name at Chicago, Cook County, Illinois.

85 JAMES LESLIE YOUNGHUSBAND.
